SAW FRAME

Andrew H. Carlson, Worcester, Mass., assignor to
 Parker Manufacturing Company, Worcester,
 Mass., a corporation of Massachusetts

Application April 29, 1944, Serial No. 533,348

3 Claims. (Cl. 145—33)

1

This invention relates to saw frames and the object is to provide a frame of simple and rugged construction which permits the blade to be quickly inserted in the frame and brought to the proper state of tension and as quickly released therefrom. The frame may be similar to those commonly used with hack saws and thus generally of U-shape with a manipulating handle at one end, and for purposes of illustration there is shown in the accompanying drawings and will hereinafter be described by way of example a construction of such frame suitable for a hack saw. In the drawings:

Fig. 1 is a side elevation of the frame with the blade in place;

Fig. 2 is a view of the handle end of the frame with parts broken away;

Fig. 3 is a view similar to Fig. 2 showing the parts in another position of adjustment to permit the blade to be removed from the frame or inserted therein; and

Fig. 4 is a section on the line 4—4 of Fig. 1.

Referring now to the drawings and more particularly to Figs. 1 and 2, the frame there shown resembles the conventional hack saw frame of U-shaped form and it may be of adjustable length to accommodate blades of different lengths, and the portion at the left of the figure is herein shown as comprising an angular member of flat metal of sufficient width to provide the desired rigidity having a depending arm 6 with studs 8 carried thereby and extending at right angles one to another, to which the forward end of the blade may be secured either to lie in the plane of the frame or at right angles thereto. This angular member comprises also the horizontal portion 10 forming the forward portion of the back of the frame which telescopes into a channel member 12 forming the cooperating portion of the back and wherein it is secured in the desired position of adjustment by any suitable or usual means, as, for example, the cross-pin 14 shown adapted to engage the notches 16 in the arm 10.

The flanges 18 of the channel 12 toward the right of the frame are extended downwardly to provide cheek portions 20 between the lower parts of which is pivoted on cross-pin 22 an arm 24 having at its lower end the studs 26 to engage the end of the blade. When this arm is held in the position of Fig. 2, it holds the blade under the desired tension. If released so that it is free to swing clockwise to the position of Fig. 3, the blade may easily be removed from the studs 8 and 26 or a blade placed in position on such studs.

2

To control the position of the arm there is provided between the flanges 18 of the channel (the word "flanges" here includes adjacent portions of the extensions of the flanges proper to form the cheeks 20) a cam or eccentric 27, conveniently of substantially elliptical form as shown with its center of rotation adjacent one end of the minor axis, which cam opposes the upper end 29 of arm 24, that end desirably being offset forwardly as seen in Figs. 2 and 3. A shaft 31 (see Fig. 4) is journalled in the flanges 18 of the channel, on which shaft the cam 27 is non-rotatably mounted. A head 33 on one end of the shaft overlies one flange of the channel and, on the other end an operating lever 35 is fitted, which lever preferably takes the form of an arm oriented with respect to the cam. Thus with the lever arm 35 extending horizontally and forwardly in the full line position of Fig. 1, the high portion of the cam opposes the end 29 of the arm, as illustrated in Fig. 2, with the lower end of the arm swung to the right in the figures to put tension on the blade, but if moved to the dotted line position of Fig. 1 the low portion of the cam opposes the arm, as seen in Fig. 3, permitting the arm to swing clockwise so that the blade may be released. The surface of the arm which opposes the high point of the cam, as seen in Fig. 2, is preferably formed on an arc which fits the surface of the cam in this position throughout an extended arc 37 to provide a secure bearing between the parts in this position.

The frame is provided with a manipulating handle 39, herein shown as of the pistol grip type, 35 which may be attached to the frame as by means of a tang 41 fitting into the channel and secured thereto by the welds 43. The eccentric 27 is disposed between the end of the tang and the offset end 29 of arm 24, permitting the grip to be positioned closely adjacent the frame proper.

In the construction shown the cam shaft 31 may rotate freely and indefinitely. Hence, referring to Fig. 1, the lever arm 35 may be turned either clockwise or counterclockwise in passing from the full line position to the dotted line position or vice versa. The movement from the position of Fig. 3 to the position of Fig. 1 is for a full 180° providing for easy operation yet for powerful tension on the blade. The handle 39 is unobstructed and rigid with the frame. This not only facilitates use of the saw but the frame also may be held by the handle in an easy and comfortable grip while the fingers of the other hand manipulate the lever 35. The cam 27 and its co-operating follower are concealed and protected.

The cam-actuating lever 35 may lie along the side of the channel out of the way and is not likely to catch or foul while it is easy of access.

I am aware that the invention may be embodied in other specific forms without departing from the spirit or essential attributes thereof, and I therefore desire the present embodiment to be considered in all respects as illustrative and not restrictive, as in fact clear in several matters from the description itself. Reference is to be had to the appended claims to indicate those principles of the invention exemplified by the particular embodiment described and which I desire to secure by Letters Patent.

I claim:

1. A saw frame having a back having a hand grip secured thereto, which back is formed by a channel, the flanges of which are extended at one end of the frame to provide cheek portions, blade-supporting arms extending from the channel at the ends of the back and one of which arms is pivoted intermediate its ends between the cheek portions, a shaft journalled in the flanges of the channel adjacent the upper end of the said one arm, an eccentric on the shaft housed between the flanges and capable of complete and continued rotation and at all times received within the outlines of the flanges, the eccentric opposing the said one arm adjacent its upper end, an end of the shaft projecting to the exterior from one flange, an operating lever at the outer side of the channel fixed to the shaft in oriented position relative to the eccentric and overlying the flange within the outline of its margins when the rise portions of the eccentric oppose the arm.

2. A saw frame having a back formed of a channel, the flanges of which are extended at one end of the frame to provide cheek portions, a hand grip having a tang entering between and secured to the flanges at said one end of the back, a shaft journalled in the flanges and supporting an eccentric closely adjacent the inner end of the tang, the eccentric being housed between the flanges and at all times received within the outlines thereof, blade-supporting arms extending downwardly from the back at either

end and including at the handle grip end an arm pivoted intermediate its ends between said cheek portions, the upper end of the arm being offset to oppose the eccentric, an end of the shaft projecting to the exterior of the channel and having an operating lever fixed thereto which overlies the flange within the outline of its margins when the rise of the eccentric opposes the arm.

3. A saw frame having a back having a hand grip secured thereto, which back is formed by a channel, the flanges of which are extended at one end of the frame to provide cheek portions, blade-supporting arms extending from the channel at the ends of the back and one of which arms is pivoted intermediate its ends between the cheek portions, a shaft journalled in the flanges of the channel adjacent the upper end of the said one arm, an eccentric on the shaft housed between the flanges and at all times received within the outlines thereof, the eccentric opposing the said one arm adjacent its upper end, an end of the shaft projecting to the exterior from one flange, an operating lever at the outer side of the channel fixed to the shaft in oriented position relative to the eccentric and overlying the flange within the outline of its margins when the rise of the eccentric opposes the arm.
